The ornamental design for a trash bag holder for waste
baskets, as shown and described.

[22] Filed: May 26, 1986

DESCRIPTION

[52] U.S. Cl. D34/6; D6/553;
D8/380

FIG. 1 is a top perspective view of a trash bag holder
for waste baskets showing my new design;

FIG. 2 is a front perspective view thereof as applied to
a round waste basket;

FIG. 3 is a front elevational view thereof;

FIG. 4 is a rear elevational view thereof;

FIG. 5 is a side elevational view thereof, the opposite
side elevational view being a mirror image of that
shown.

The broken lines of the waste basket's bottom portion
shown in FIGS. 1 and 2 are for illustrative purposes
only and form no part of the claimed design.
